UNITED STATES PATENT OFFICE.

HENRY AUGUSTUS SMITH, OF LOS ANGELES, CALIFORNIA.

VENTILATED FRUIT AND REFRIGERATOR CAR.

SPECIFICATION forming part of Letters Patent No. 498,449, dated May 30, 1893.

Application filed September 6, 1892. Serial No. 445,182. (No model.)

To all whom it may concern:

Be it known that I, HENRY AUGUSTUS SMITH, a citizen of the United States, residing at Los Angeles, in the county of Los Angeles and State of California, have invented a new and useful Ventilated Fruit and Refrigerator Car, of which the following is a specification.

One object of my invention is to provide superior means for transportation of fruit which will economize ice where refrigeration is required and which will more effectually ventilate the fruit than is possible in railway cars of the present construction.

My improved car is adapted for the ventilation of the sides, ends and the bottom and top of the car, while the body of the car is closed and I provide a cowl extension at each end of the car so as to force a draft of air between the ceiling and roof and also through the body of the car while in motion, when desired; the car being provided with means for opening and closing the ventilating appliances from the outside of the car, and for changing it from a ventilated car into a closed car for handling fruit in a cold climate.

My improved car is provided with removable ice boxes so that the car can be adapted for use as a common box car, a ventilated fruit car or a refrigerator car as occasion may require.

A further object of my invention is to apply the principle of dry air refrigeration to cars.

A further object is to provide a refrigerator car of less weight than those now in vogue.

A further object is to provide a ventilated car with means which will retain within the car when standing, the cold air which has been produced within the car while the car was in motion.

The accompanying drawings illustrate my invention.

Figure 1 is a vertical longitudinal mid-section of a car embodying my invention. Fig. 2 is a view of the car with the outside portion or member of its side wall removed. Fig. 3 is an enlarged detail of one end of Fig. 1 and a fragment of the middle of the car. Fig. 4 is an end view of the car with the main ventilator open into the body of the car. Fig. 5 is a cross-section on line $x-x$ of Fig. 1 looking toward the body of the car. Fig. 6 is a cross-

section on line $y-y$ of Fig. 1 looking to the right. Fig. 7 is a detail of the ice box. Fig. 8 is a detail, in elevation and plan views, of the ventilator ratchet. Fig. 9 is a fragmental cross sectional detail of the rim of the ice box and the ceiling and the packing therebetween.

My improved car has hollow side walls $A A'$ provided respectively with a chamber closed at the bottom and throughout except that it is arranged to communicate at the top with a ventilating chamber B which is arranged between the roof and the ceiling of the car and is arranged to communicate with the top ventilators $D D'$ arranged above the level of the ceiling at the ends of the car, so that when the ventilators D, D' are open and the car is in motion a draft of air will be produced through the chamber B between the roof b and ceiling b' to prevent the stagnation and accumulation of heated air in the chamber B and also to allow a circulation of air in the several chambers $a a'$ within the walls. By this construction the air within the walls will have sufficient circulation to prevent stagnation and objectionable heating of the air in the walls, as the air will slowly descend within the vertical chambers on the side next the cold main or body chamber of the car and will slowly ascend next the outside wall and this action will be increased by the draft caused through the chamber B , when the car moves. This arrangement is designed to protect the interior of the car from the objectionable effects of the hot sun without serving to conduct heat into the main body of the car.

The ends of the car are provided with double end walls $E e$ and $E' e'$ which are provided respectively with the elevated outer ventilators F, F' and the lower inner ventilators f, f' . These ventilators are provided respectively with suitable shutters $G G'$ and $g g'$. The chambers $H H'$ within the hollow end walls of the car are arranged to communicate with the chamber B at the top of the car. A floor chamber J is provided beneath the floor K of the car and extends from end to end of the car and is closed throughout, except that it communicates with the end wall chambers H and H' respectively so that when the shutters $G G'$ and $g g'$ are closed and the ventilator D is open, the draft of air through

the chamber B will serve to prevent stagnation of the air within the chambers H H' and J. Ventilators L L' are provided in the inner members e, e' of the end walls and their 5 shutters are provided with suitable means such as the rod l to be operated from the outside of the car to admit air into the body of the car when desired.

The ventilator shutters G g (G' g') are connected by suitable means with raising and lowering mechanism M (M') arranged to raise 10 one of the shutters and lower the other shutter at the same time.

The ventilator opening F (F') in the upper 15 half of the outer member of the end wall extends down to a point four or five feet above the floor of the car and the ventilator opening f (f') in the lower half of the inner end wall extends up nearly to the same level and 20 the shutters G g (G' g') are respectively arranged, the one to close the outside opening from bottom to top and the other to close the inside opening from top to bottom so that when the shutters are adjusted to fully open 25 the ventilators F f the shutter G will be fully lowered and the shutter g will be fully raised.

The mechanism for raising and lowering the shutters consists in the drum m m' mounted upon a shaft N, which shaft is journaled in 30 the wall of the car and extends upon one side to the outside thereof where a pawl and ratchet P O and a crank stem Q are provided for the rotation of the shaft and for securing the same in desired position. A crank R is provided 35 for the operation of the shaft.

16 and 17 indicate cords or chains secured to the shutters and wound upon the drums to sustain and raise and lower the shutter.

The outer openings of the ventilator are 40 provided with wire screens r to exclude cinders. In the chambers H H' a guard h is provided to prevent the dirt from falling into the floor chamber J.

S S' indicate guides to guide the shutters G 45 and g (G' g') respectively to hold them to tightly close the ventilator F and f (F' f'). The guides slope toward that end of the ventilator opening into which the shutter advances to close the opening, and the rear end 50 of the shutter (i. e., the end which last enters the ventilator opening in the act of closing the same) is provided with beveled shoulders T arranged to engage a shoulder stop or cross bar U (U') at the latter part of the movement 55 of the shutter in closing the ventilator so that the rear end of the shutter will be forced into the opening at the latter part of the movement of closing the ventilator.

The member E of the wall at the lower edge 60 of the ventilator opening F is beveled so that when the raising appliances M are manipulated to allow the shutter to lower, the shutter will slide down out of the opening by its own weight; and the wall e is beveled at the top of the opening f so that when the shutter 65 is raised it will be easily forced out of such opening to be carried on up the guide groove S'.

V indicates paper lining or other non-heat-conducting substances with which the car is insulated.

All the openings of the ventilators and doors are provided with rubber or other insulating material V' to exclude air and heat.

W indicates independent removable ceiling 70 ice boxes which are arranged longitudinal of the car and are hermetically sealed by rubber packing X or other suitable material for insulating such boxes and for preventing the passage of air between the box and the top of the main chamber of the car. These boxes 75 are provided with sheet metal walls of zinc, galvanized iron or other suitable material and have their floors sloping from one end to the other. In the drawings these floors are shown sloping from the middle of the car toward 80 each end of the car. These boxes are supported in position by removable cross beams 85 Y which rest upon side cleats Z.

w, w' are cleats on the ceiling to hold the ice boxes in proper position.

Each of my newly invented removable ceiling ice-boxes for refrigerator cars comprises the sheet metal walls w'; and floor w'', the externally arranged drip tray base i arranged beneath the floor and walls and secured there- 95 to by intermediate means, such as the cleats 50, with a space between the floor and the drip-tray base, and the packing X at the top of the walls. The drip-tray base i is arranged beneath the floor of the ice box to 100 catch the drip of the condense which will form upon the metal walls of the ice boxes when such boxes are provided with ice and the car has within it fruit or other substances from which there is evaporation.

j is the waste pipe through which the condense finds discharge, passing thereinto through the opening k.

The ice box is provided with the internal 110 ice rack 51 of common construction and the waste pipe j leads from the inside of the box below the top of the rack to drain off the water from the melted ice. By means of my peculiarly constructed ice box I am enabled to provide the car with effective ceiling-ice-boxes 115 which can be removed and replaced at pleasure. If it is desired to use my improved car for bulky freight which does not require refrigeration, the ice-boxes can be removed and stored and afterward replaced when required. 120 Each box is complete within itself and to convert the fruit car into a refrigerator car, the boxes are placed in position within the car with the packing X against the ceiling, and is then secured by suitable means such as the 125 beams Y.

2, 2 indicate the ice box chutes closed with suitable plugs and covers 3, 4. A cowl 5 is provided at each end of the car to catch the air and to force it into the ventilators when 130 the same are opened and the car in motion. These cowls project out endwise from the car about six inches.

A suitable lock is provided for the pawl P.

so that the same can be locked in position to prevent accidental displacement. This lock consists of a rear hinge-extension 7 hinged to the pawl and arranged to slip over a staple 8 (secured to the car) when the pawl is resting in the notch of the ratchet as shown in Fig. 8. If desired a padlock or seal or other suitable means can be used to prevent tampering with the ventilators, the same being inserted 10 through the staple.

In practice when the car is to be used as a ventilator fruit car the fruit is loaded into it in the ordinary manner and the shutters G, g, G', g' of the end ventilators are adjusted 15 to give such opening therethrough as is considered necessary to produce the draft through the car which may be desirable while the car is in motion. The ventilators D D' are also opened to allow a draft of air through the chamber B in the top of the car. When the car is moving the air passes through and prevents 20 stagnation of air within the wall and floor chambers and the air passing through the body of the car carries off the exhalations from the cargo and preserves the fruit. The 25 ventilators L L' are opened to draw off the air from the top of the main chamber of the car. When the car is to pass through a cold climate the several ventilators are closed, 30 thus transforming the car into an insulated car which will prevent the escape of heat, and consequent freezing of the cargo.

When it is desired to use the car as a refrigerator car, the ice boxes being placed in 35 position, the same are filled through the chutes 2 and the body ventilators F, f, F', f' are closed and the top ventilators D D' are also closed but such ventilators D, D' may be advantageously opened at night or when the atmosphere is cool to allow circulation of air in 40 the surrounding chambers B, H, a, a' and J. The ventilators L L' are designed for use only when ice is not used. Any condense which may form from the atmosphere within the car 45 which comes into contact with the cold sheet metal walls of the ice box, will be collected by the tray i and thence flow into the drip pipe J through the opening k and the water from the melting ice within the box will be 50 conducted out of the car through such pipe j which is trapped at its lower end to prevent ingress of air.

The braces 9, 10 in the hollow side walls of 55 the car are each equal in thickness to half the chamber a, thus leaving space for free circulation of air between the outside and inside members (11 and 12) of the wall. The floor is laid upon the joists 13, and braces 14 are arranged between such joists; but such 60 braces do not extend up high enough to shut off communication between the different parts of the floor chamber J.

By making the side walls hollow and closed 65 throughout except at the top, the movement of air therein is slight, being only sufficient to prevent stagnation, while if the side chamber communicates with the exterior air or

with the air in the body of the car, the draft of air through the side chambers is more rapid than is necessary to properly cool the 70 car, and the result, instead of being a perfect insulation such as I secure, will be a diminished insulation and the circulation will tend to warm the interior of the car.

It is to be understood that the damp air 75 from the inside of the ice-box does not enter the car and that the drip tray does not receive any of the drip from the ice, its purpose being simply to receive the drip or moisture from the interior of the car exterior to the 80 ice box, which condenses upon the outside of the metallic walls of the ice box, the same being taken from the air within the car and not from the air which comes in contact with the ice. 85

Now, having described my invention, what I claim as new, and desire to secure by Letters Patent, is—

1. The improved car having the top ventilators at the ends of the car and a ventilating chamber between the roof and the ceiling of the car communicating with the top ventilators and having the hollow side walls provided with chambers closed throughout, except that they are arranged to communicate 95 at their tops with such ventilating chamber.

2. The improved car set forth having hollow end walls and having hollow side walls the chambers in which are closed throughout except at the top and provided with the top 100 ventilating chamber arranged between the roof and ceiling of the car and communicating with the tops of the chambers in the side-walls and with the tops of the chambers in the end walls and with the ventilators in the 105 ends of the car, and having the floor chamber beneath the floor of the car closed throughout except that it is arranged to communicate with the chambers in the end walls of the car. 110

3. The improved car set forth having the hollow end walls provided respectively with the elevated outer ventilators F F' and the lower inner ventilators f f' provided with suitable shutters, and having the chambers 115 H H' within the hollow end walls of the car arranged to communicate with a ventilating chamber arranged in the top of the car between the roof of the ceiling and communicating with ventilators arranged in the ends 120 of the car.

4. A car comprising the combination of the hollow end wall provided with the outer member having a ventilator in its upper half and with an inner member having a ventilator in 125 its lower half; a shutter arranged to close the outer ventilator from the bottom upward; a shutter arranged to close the inner ventilator from the top downward and means for operating such shutters to raise the outer 130 shutter and close the outer ventilator and at the same time to lower the inner shutter and close the inner ventilator.

5. The combination of the inner wall mem-

ber provided in its lower half with the ventilator opening; the shutter guides sloping downward toward the bottom of the ventilator opening; the shoulder stop, and the shutter arranged to slide in such guides and provided with beveled shoulders arranged to engage the shoulder stop at the latter part of the movement of the shutter in closing the ventilator so that the rear end of the shutter will be forced into the opening at the latter part of the movement of closing the ventilator.

6. A car comprising the combination of the outer member of the hollow-end wall provided with a ventilator opening; the shutter guides sloping at the top toward the ventilator opening; the shoulder stop, and the ventilator shutter arranged to slide in the guides and provided with the beveled shoulder arranged to engage the shoulder stop at the latter portion of the upward movement of the shutter.

7. The combination of the car wall provided

with a ventilator opening; shutter guides sloping at one end toward the ventilator opening; the shoulder stops, and the ventilator shutters arranged to slide in such guides and provided with beveled shoulders arranged at the rear end of the shutter to engage the shoulder stops to force the rear end of the shutter into the ventilator opening at the close of the movement of the shutter in closing the ventilator opening.

8. In combination in a refrigerator car the independent removable ceiling-ice-box comprising the sheet metal walls and floor, the externally arranged drip tray base arranged beneath the floor and walls and secured thereto by suitable means, such means, and the packing at the top of the walls.

HENRY AUGUSTUS SMITH.
